UNITED STATES PATENT OFFICE

GOTTFRIED GOETZ, OF WEBSTER GROVES, MISSOURI, ASSIGNOR TO LUDWIG KERN, OF WEBSTER GROVES, MISSOURI

TRAVELING LOADING DEVICE

Application filed July 21, 1932. Serial No. 623,704.

This invention relates to traveling loading devices, and with regard to certain more specific features, to traveling loading devices adapted particularly for the loading 5 of carbonizing vertical coking retorts with briquettes or like shaped objects.

Among the several objects of the invention may be noted the provision of a traveling loading device of the class described which 10 is adapted to receive uncarbonized briquettes, as from a hopper, and place them in the interior of a coking retort, in such manner that the briquettes are not subjected to great falls or disruptive forces at any time; the 15 provision of a device of the class described which is adapted for ready installation in connection with an entire bench of coking retorts, and which may be used with equal facility for any retort in the bench; the provision of a device of the class described which 20 includes telescoping means whereby, at the time the charge is delivered to the retort, the device extends substantially to the bottom of the retort; and the provision of a 25 device of the class described which is relatively simple in construction and operation. Other objects will be in part obvious and in part pointed out hereinafter.

The invention accordingly comprises the 30 elements and combinations of elements, features of construction, and arrangements of parts which will be exemplified in the structures hereinafter described, and the scope of the application of which will be indicated 35 in the following claims.

In the accompanying drawings, in which is illustrated one of various possible embodiments of the invention,

Fig. 1 is a side elevation of a crane embodying the present invention, the charging means being shown in tilted position ready to receive a charge;

Fig. 2 is a side elevation similar to the crane of Fig. 1 with the charging means in 45 vertical position ready to be lowered into a retort;

Fig. 3 is a side elevation similar to Fig. 2, partly in section, showing the charging means in lowered, extended position in the 50 interior of a retort; and,

Fig. 4 is a front elevation of the crane shown in Fig. 2.

Similar reference characters indicate corresponding parts throughout the several views of the drawings.

It has long been considered disadvantageous to use vertical carbonizing or coking retorts of the class generally used to coke coal, for carbonizing briquettes, principally because no satisfactory means have heretofore been provided for charging said retorts with the uncarbonized briquettes. Uncarbonized briquettes, it will be understood, are of a fragile nature and will not in general withstand the disruptive forces occasioned by their falling from the top to the bottom of the vertical retort as the retort is filled. Such raw briquettes cannot in general be safely dropped more than a few feet at the most. The present invention provides a 60 charging means whereby vertical coking retorts of the class described may be satisfactorily utilized for the carbonization of briquettes, in that it provides means whereby the retorts are filled with briquettes without at any time necessitating any particularly 65 long fall for such raw briquettes.

Referring now more particularly to Fig. 1, numeral 1 indicates a bogie wagon which runs on wheels 3 on tracks 5 provided on top of the retort bench 7. Numerals 9 indicate, diagrammatically, the individual retorts of the bench. The bogie wagon 1 comprises a suitable rectangular frame work of steel beams or the like, having a superstructure comprising sloping uprights 11 and top pieces 13 on each side thereof. The superstructure is desirably reenforced by bracing beams 15 (see Fig. 4), and horizontal beams 17. All of the beams 11, 13, 15 and 17 desirably constitute steel channel beams or the like.

At one end of the bogie wagon 1 is provided a driving motor 19, which by means of a suitable transmission drives the wheels 3 to run the wagon as a whole along the top of the retort bench. The motor 19 also drives a drum 21, which is utilized as hereinafter described.

Numerals 23 indicates a charging means or loading basket comprising a top funnel or

hopper portion 25 and a lower extending portion 27. The extended portion 27 comprises telescoping members or sections 29 and 31 (see also Fig. 3), the portion 29 telescoping exteriorly of and surrounding the portion 31. The portion 31 is permanently affixed to the hopper portion 25, while the portion 29 slides upon the portion 31.

A reenforcing band 33 is provided around the upper end of the portion 29, and extending from each side of the band 33 is a trunnion 35. The trunnions 35 are held in a sliding block 37, which has a slot 39 therein in which the trunnions 35 may slide. The block 37 in turn slides in open-ended tracks 41 mounted on the superstructure of the bogie wagon.

Attached to the top of the sliding block 37 is a wire cable 43, which passes upwardly over an idler pulley 45 and thence to the drum 21 driven by the motor 19. As will be disclosed more fully hereinafter, the wire cable 43 comprises the means for letting the charging device down into the interior of the retort, as it is paid out from the drum 21.

The lower end of the outermost telescoping portion 29 is provided with a pair of hinged doors 47 which swing together completely to close the bottom of said portion 29. Pivotal secured to the inner, swinging edge of each door 47, at each end of the portion 29, are links 49, which are pivoted at their other ends, respectively, to blocks 51, which slide in suitable guides mounted on a band 57 surrounding the section 29. The blocks 51 have an outward projection 53 thereon, which serves for latching purposes as will be described hereinafter. From the top of the block 51 a link or cable 55 extends to the bottom of the sliding block 37.

A second reenforcing band 57 is provided near the bottom of the telescoping portion 29 in the region of the block 51. On the band 57 are mounted a pair of pawls 59, which are pivoted in such manner that, with the device as in the Fig. 1 position, they do not interfere with the action of the block 51, but when said block 51 is lowered, the pawls 59 rotate and lock around the projection 53. The purpose of this arrangement will be apparent in the description of the operation hereinafter.

A third reenforcing band 61 is provided at the telescoping portion 29 between the bands 33 and 57.

Mounted on the bogie wagon 1, at each side thereof (see Fig. 4) is a pair of pawls 63, which are rotatably pivoted on bolts 65. With the pawls 63 upstanding, as illustrated in Fig. 4, they do not interfere in any manner with the movement of the charging means, but when said pawls are swung inwardly on their pivots, they are in position to engage the reenforcing band 61 to prevent lowering of the charging means into a retort. This

arrangement may be utilized when it is desired to stop the charging device for a time, such as when a charge has already been placed therein, or to permit charging under conditions allowing free fall of the material to the bottom of the retort. 70

Also mounted on the bogie wagon 1 (see Fig. 1) are a pair of stops 67, which are spaced apart a sufficient distance to engage the pawls 59 on movement of the telescoping portion 29 in an upward direction, but to clear said pawls 59 on downward movement of the telescoping portion 29, for purposes to be described. 75

Sidewardly mounted upon the superstructure of the bogie wagon is a transverse shaft 69, which is supported in bearings 71, and which is provided with a series of drums 73 thereon. Affixed to the drums 73 are chains 75, which are provided at their ends with hooks or rings 77 adapted to engage eyes 79 mounted in the side of the hopper portion 25. The shaft 69 is also provided with a hand wheel 81 and a ratchet wheel 83 and pawl 85 for maintaining the hopper portion 25 80 in any desired angular position. 85

The operation of the device is substantially as follows:

The initial position of the charging device is, for example, that shown in Fig. 2, where the telescoping portions 29 and 31 are collapsed and vertical, and the discharge doors 47 are closed. The first step in filling the retort comprises driving the bogie wagon to a position under a charging hopper 87 indicated diagrammatically in Fig. 1, where it is to be filled with the raw briquettes. Having arrived in such position, the entire charging means is now tilted on the trunnions 35 by suitably manipulating the hand wheel 81 to run up the chains 75 on the drums 73. As this is done, the entire hopper and telescoping portion assembly comes into the sloping position shown in Fig. 1, relative to its vertical axis. In this position the raw briquettes are allowed to run from the hopper 87 into the hopper portion 25, the general slant of the whole device eliminating the necessity for the raw briquettes to fall freely for any distance whatsoever. 100 105 110 115

It will be appreciated that the entire weight of the charging means is supported, through the trunnions 35, by the wire cables 43.

When the telescoped portions 29 and 31 have been filled, and an additional volume of briquettes loaded into the hopper portion 25, the charging means 23 is now allowed to right itself by again manipulating the hand wheel 81. The device is now in position for lowering into a retort to discharge its load of raw briquettes. The loading of too many briquettes into the hopper portion 25 is preferably avoided, as this would shift the center of gravity of the charged loading means into the hopper portion 25 and prevent righting 120 125 130

of the charged loading means when the chain 75 is paid out.

The bogie wagon is run to the retort desired to be filled, at which time the motor 5 19 and drum 21 are manipulated so that the cable 43 is slowly paid out. Under these circumstances, the entire charging means is first gradually lowered toward the mouth of the selected retort 9, the sliding 10 block 37 meanwhile passing out of its tracks 41. As the telescoped portions 29 and 31 sink into the retort, projecting stop bars 89 (see Figs. 3) on the hopper portion 25 abut suitably positioned stop bars 91 mounted on 15 the platform of the bogie wagon. This prevents further lowering of the hopper portion 25 of the charging device 23.

As the cable 43 is further paid out, the next thing that happens is that the section 20 29 extends telescopingly away from the section 31, and continues so to do until a top flange 93 on the portion 29 abuts a bottom flange 95 on the portion 31, in such manner that further extension is prevented. In this 25 downward motion, the pawls 59, being in the retracted position, clear the stops 67. While the extension has been taking place, the briquettes flow without any falling, from the hopper portion 25 into the upper telescoping portion 31, and when the telescoping portions 29 and 31 are fully extended, substantially no briquettes remain in the hopper portion 25.

As the cable 43 is still further paid out, the 30 weight of the briquettes upon the doors 47 presses said doors open and by this time the bottom of the portion 29 has reached almost to the bottom of the retort, and as the doors 47 open, the briquettes experience but a very 35 short fall before they are definitely stopped by the bottom of the retort. Finally, the cables 43 are paid out to such an extent that the projection 53 of the block 51 becomes locked between the pawls 59. Effectually, 40 this means that the doors 47 are locked open.

The direction of rotation of the drum 21 is now reversed, and the cables 43 rewound thereon. The upwardly moving cable cannot reclose the doors 47 because of the engagement 45 of the pawls 59 and the projection 53, but it does slowly pull the entire lower section 29 again into retracted, telescoped position upon the section 31, meanwhile delivering the charge of raw briquettes into the retort. All of this delivering of briquettes goes on without said briquettes falling through any appreciable distance, and thus their breaking is avoided.

After the sections 29 and 31 have completely telescoped, further pulling on the cable 43 lifts the entire charging means 23 back up out of the retort, and slowly returns said charging means to its Fig. 2 position. As the pawls 59 pass the projections 67, their 50 sidewardly extending portions, being now in

extended position, are engaged and rotated downwardly, thus opening the claw portions and releasing the projection 53. Thereupon the piece 51 moves upwardly relative to the section 29, and, by means of the links 49, 70 doors 47 are closed, and the device again becomes supported solely by the trunnions 35 resting in the ends of the slots 39 in the blocks 37. The device is now ready for reloading and charging another retort. 75

One or more stops 97 is desirably provided on the upright beams 11 in order to bear part of the weight of the charging means 23 when in its sloping, Fig. 1 position.

As indicated in Fig. 4, the bogie wagon 1 80 may be sufficiently wide to accommodate several charging means 23, as for a retort bench in which several retorts are located one behind another. Or, the bogie wagon may carry but one such charging device 23. 85

From the above it will be seen that the invention provides a means whereby the raw briquettes may be carefully handled, without any substantial fall, from the bins in which they are accumulated after briquetting up until the time they are deposited in the retort for coking. 90

In view of the above, it will be seen that the several objects of the invention are achieved and other advantageous results attained. 95

As many changes could be made in carrying out the above constructions without departing from the scope of the invention, it is intended that all matter contained in the above description or shown in the accompanying drawings shall be interpreted as illustrative and not in a limiting sense. 100

I claim:

1. A loading device for retorts and the like comprising supporting means, charging means comprising telescoping sections adapted to be extended downwardly into the retort, cables supporting said charging means upon said supporting means, power means for paying out and taking in said cables to lower and raise the charging means within the supporting means, and trunnion joints by means of which said cables are attached to said charging means, whereby said charging means may be swung from its vertical axis in said supporting means. 110

2. A loading device for retorts and the like comprising supporting means, charging means comprising telescoping sections adapted to be extended downwardly into the retort, cables supporting said charging means upon said supporting means, power means for paying out and taking in said cables to lower and raise the charging means within the supporting means, and trunnion joints by means of which said cables are attached to said charging means, whereby said charging means may be swung from its vertical axis in said supporting means, and means for swing- 120 125 130

ing said charging means from its said vertical position.

3. A loading device for retorts and the like comprising supporting means, charging means comprising an upper hopper section and lower telescoping sections, the outermost of said telescoping sections being adapted to extend downwardly from the remaining sections, cables attached to said outermost section and normally supporting the entire charging means, means for paying out and taking in said cables, whereby to raise and lower said charging means in said supporting means, means on said supporting means whereby, when said charging means is lowered to a predetermined extent, said hopper section is supported directly upon said supporting means, and whereby, upon further paying out of said cables, said outermost section extends telescopingly downwardly from the remaining sections, and trunnion joints by means of which said cables are attached to said outermost section, whereby said charging means may be swung from its vertical axis within said supporting means.

4. A loading device as set forth in claim 1, including closure means at the lower end of the outermost telescoping section, and means connecting said closure means and said cables whereby, when said outermost section is extended to its greatest extent, further pay-

ing out of said cables opens said closure means.

5. A loading device as set forth in claim 1, including closure means at the lower end of the outermost telescoping section, means for operating said closure means, and means controlling said operating means according to the position of said charging means, such that said closure means are opened only when said outermost telescoping section is in its fully extended position, and such that said closure means thereafter remain opened as said outermost section is retracted telescopingly into said charging means.

6. A loading device as set forth in claim 1, including closure means at the lower end of the outermost telescoping sections, means connecting said closure means and said cables whereby, when said outermost section is extended to its greatest extent, further paying out of said cables opens said closure means, and locking means automatically securing said closure means in opening position once said closure means is opened in the manner set forth, whereby taking of said cable to retract said extended telescoping section is ineffectual to close said closure means.

In testimony whereof, I have signed my name to this specification this 18th day of July, 1932.

GOTTFRIED GOETZ.
